(57) **CLAIM**

The ornamental design for a flat griddle, as shown and described.

DESCRIPTION

FIG. 1 is a front perspective view of a flat griddle, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof; and,

FIG. 9 is a partial enlargement of FIG. 1.

The dashed broken lines illustrate portions of the flat griddle that form no part of the claimed design. The dot-dashed broken lines depict reference to the enlargements within the drawings and show the boundary of the enlarged view and form no part of the claimed design.
